GAME

Gustave Erickson, Chicago, Ill.

Application April 5, 1935, Serial No. 14,775

13 Claims. (Cl. 273—142)

This invention relates to a game or amusement device and has for its principal object the provision of an entertaining game.

A further object of the invention is to provide a game apparatus in which two controlling factors, which may arise during the play, are combined to provide a variable result depending upon the nature of said factors.

A further object of the invention is to provide a game simulating a horse race, which can be played in a competitive manner by two or more teams or parties.

A further object of the invention is to provide a game apparatus having two counters or recorders and automatic means whereby each counter is connected operatively in alternation to permit the score of each player to be recorded separately.

This invention will readily be understood from the following description of a preferred embodiment thereof taken in conjunction with the accompanying drawings, in which

Figure 1 is a plan view of the game apparatus enclosed within a cabinet;

Fig. 2 is a sectional plan view taken on the line 2—2 of Fig. 3, showing the mechanism;

Fig. 3 is a front elevational view of the mechanism removed from the cabinet;

Fig. 4 is a vertical section through the mechanism taken on the line 4—4 of Fig. 2;

Fig. 5 is an inverted sectional plan taken on the line 5—5 of Fig. 3;

Fig. 6 is a sectional detail view taken on the line 6—6 of Fig. 2;

Fig. 7 is a sectional detail view taken on the line 7—7 of Fig. 2;

Fig. 8 is a sectional detail view taken on the line 8—8 of Fig. 2;

Fig. 9 is a sectional detail view taken on the line 9—9 of Fig. 2; and

Fig. 10 is a sectional detail view taken on the line 10—10 of Fig. 4.

The embodiment of the invention shown in the drawings comprises a horse racing game in which the player selects a particular horse to win. Automatic means are provided for determining the odds for that particular horse. In the event that the player's horse wins, the appropriate number of the odds indicated for that play is added to the reading of a counter. As will be more fully described, the apparatus comprises two such counters and means whereby the counters are rendered operative alternately with repeated operations of the machine. This enables the game to be played by two parties or by two teams, the readings of

the counters indicating the success of each side.

Referring to the accompanying drawings, the reference numeral 11 designates the cabinet in which the game apparatus is located, said cabinet preferably comprising a glass cover 12 through 5 which the horses 13 may be viewed while the apparatus is being played. Each of the horses 13 is provided with a distinctive color and number. A selector handle 14 on the exterior of the cabinet is employed to enable the player to select a particular horse. This selector handle controls an indicator 15 which indicates the color and number of the horse which has been selected. The horses are put in motion, likewise the other parts of the machine, by means of a handle 16, also mounted on the exterior of the cabinet 11. A button 17 on the exterior of the cabinet 11 enables the counters 18 to be returned to zero reading when desired, as will be described more fully hereinafter.

The horses 13 are mounted in a circle adjacent the periphery of a disc 20. The disc 20 is relatively large and is mounted upon a small stout disc 21. The disc 21 is rigidly secured upon a shaft 23 which is supported on an elongated bearing 24 carried by the main plate 25 of the frame of the machine. From the disc 21 depends a cylinder 26 which is provided with a series of large holes 27 corresponding in number to the number of horses 13. In the embodiment of the invention shown, 30 six horses are provided and six openings 27 are formed in the skirt or cylinder 26. As best seen in Fig. 4, the openings 27 are arranged at different heights in the cylinder 26, the purpose of this arrangement being hereinafter more fully explained. 35

Immediately beneath the disc 20 and arranged concentric thereto is an annular plate 28, the outer diameter of which is somewhat greater than that of the disc 20. Accordingly, the plate 28 has a peripheral margin exposed beyond the periphery of the disc 20 and this margin carries indicia, as best shown in Fig. 1, which correspond, for example, to the odds to which the selected horse is entitled if he wins. A winning post 29 is provided within the cabinet and the horse 40 stopping at this post after the disc 20 is spun, is the winning horse. The odds to which that horse is entitled are shown by the indica on the plate 28 immediately in front of that horse. The 45 plate 28 is mounted on the upper end of a cylinder 30 which is concentric with and arranged around the cylinder 26. The cylinder 30 is mounted at its lower end upon a disc 31 which is provided with a boss 32 through which passes 50

the shaft 23. The boss 32 serves as a bearing for the cylinder 30 and disc 28.

A ratchet wheel 33 is mounted on the disc 31 so that its teeth project beyond the cylinder 30.

- 5 The number of teeth on this ratchet wheel correspond to the number of indicia on the plate 28, the purpose being to arrest the plate 28 with one of said indicia immediately in front of the winning horse. In the embodiment of the invention
- 10 shown, thirty such indicia are provided on the plate 28 at equal distances, and thirty teeth are provided on the ratchet wheel 33 also at equal distances. A ratchet wheel 34 is rigidly mounted on a collar 35 which is rigidly pinned to the shaft
- 15 23 so that this ratchet wheel rotates with the disc 20 and the horses 13. The ratchet wheel 34 is provided with as many teeth as there are horses 13. These teeth, like the horses, are placed at equal distances and arranged so that engagement
- 20 of the tooth by the proper detent arrests one horse at the winning post. With reference to Fig. 4, it is to be noted that the disc 31 rests upon the upper end of the collar 35. The collar 35 has rigidly mounted thereon a ratchet wheel 36 which
- 25 is adapted to cooperate with a pawl 37 pivotally mounted on the ratchet wheel 33 and disc 31. This pawl is held by spring 38 in contact with the ratchet wheel 36, as best seen in Fig. 10. As best shown in Figs. 2 and 10, the teeth of the
- 30 ratchet wheels 33, 34 and 36 are directed in a counter-clockwise direction as viewed in plan.

A ratchet wheel 39 directed in the opposite direction to that of the ratchet wheels 33, 34 and 36 is rigidly secured to the lower end of the collar 35. This ratchet wheel 39 is adapted to be engaged by a pawl 40 having a bell crank extension 41. The pawl 40 is pivotally mounted upon a bar 42 which in turn is pivotally mounted on the shaft 23. The bell crank arm 41 of the pawl 40 is engaged by a spring 43 which is secured to the main plate 25 of the machine. With reference to Fig. 2, it will be noted that when the bar 42 is rotated in clockwise direction, the pawl 40 is moved away from the point of connection of the spring 43 with the main plate 25. As a result, the nose of the pawl 40 is brought firmly into contact with the ratchet wheel 39. When the bar 42 is forcibly rotated in a clockwise direction, an event which occurs in the operation of the game, 45 as will be more fully described, the pawl 40 imparts a substantial impetus to the ratchet wheel 39, causing the shaft 23 to rotate in a counter-clockwise direction as viewed in plan. Consequently, the horses 13 are spun rapidly in that 50 direction. Engagement of the ratchet wheel 36 with the pawl 37 likewise causes the cylinder 30 and disc 28 to rotate rapidly in the same direction. This connection between the two rotating systems is such that the plate 28 may continue 55 to rotate after the disc 20 has become arrested, as will hereinafter be more fully discussed. It is noted that when the bar 42 returns to its initial position, that is, the position shown in Fig. 2, the spring 43 is no longer tensioned, and the pawl 40 60 is enabled to clear the teeth at the ratchet wheel 39 so that the spinning of the shaft 23, disc 31, and associated parts, is not impeded by the pawl 40.

The bar 42 is provided at one end with a slot 70 which receives a pin 45 carried in a sliding bar 46. This sliding bar is located on the surface of the main plate 25 and is guided thereon by means of two screws 47 which extend through slots 48 in the sliding bar. At one end the sliding bar 46 carries a pin 49 which is engaged by the slotted

end of an arm 50. The arm 50 is rigidly mounted on a vertical shaft 51 which extends through the plate 25 and through a plate 52 carried above and in spaced relation to the plate 25, being supported thereon by means of posts 53. Above the plate 52 the shaft 51 has rigidly mounted thereon an arm 54. Upon the arm 54 is pivotally mounted a pawl 55 which is biased towards a stop 56 by a spring 57. A radial arm 58 carried by the hub of the handle 16 is adapted to engage the pawl 55 so as to swing the arm 54. At a certain point, as indicated in dotted lines in Fig. 2, the arm 58 slips off the pawl 55 and the arms 54, 50 and bar 46 are rapidly moved back to their initial positions. The handle 16 is returned to its initial 10 position by a spring 58, the arm 58 slipping past the curved end of the pawl 55. The bar 54 carries a spring-pressed pawl 59 which is adapted to engage the teeth of a sector bar 60 mounted on the plate 52. The relation of the pawl 59 and bar 20 60 is such that a full stroke must be made before the handle 16 can be returned. This return is effected by a spring 62 which is secured to the bar 46 and to a screw in one of the posts 53.

Thus it will be understood that when the handle 16 is actuated, it must be thrown to its fullest extent. When the arm 54 becomes disengaged from the pawl 55, the spring 62 throws the bar 46 forcibly towards the right, as viewed in Fig. 2, and the disc 20 and plate 28, together with 30 the elements secured thereto, are spun sharply in a counter-clockwise direction as viewed in plan.

The bar 46 is provided with an upstanding pin 63 which is adapted to engage a lever 64 pivotally mounted on the plate 25 by means of a shaft 35 65 65 upon which the bar 64 is rigidly mounted. This lever is drawn firmly to the right, as viewed in Fig. 2, by means of a spring 66 secured to the lever 64 and to a part of the main frame of the machine. When the handle 16 is actuated, the 40 bar 46 is moved to the left, as viewed in this figure, and the pin 63 moves the lever 64 with it. The shaft 65 projects downwardly to the underside of the plate 25 and has rigidly mounted thereon a ratchet 67, shown in dotted lines in 45 Fig. 5. When the lever 64 moves to the left, as viewed in Fig. 2, the teeth of the ratchet 67 slip past pawls 68 which are carried by a pinion 69 freely rotatable upon the shaft 65. The pawls 68 are biased by springs into contact with the ratchet 50 67. The pinion 69 forms part of a train of gearing whereby rotation of the shaft 65 in the opposite direction, that is, the counter-clockwise direction as viewed in Fig. 2, effects, through a suitable train of gearing, the driving of a vane 70 55 below the plate 25. This mechanism amounts merely to a clockwork dashpot and is well known in this art. The effect of the vane 70 is that the return of the lever 64 is relatively slow and enables the disk 20 and plate 28 to continue spinning for a substantial period of time corresponding to a race period.

The lever 64 controls the operation of a latch element 71 which is pivotally mounted on the plate 25 at 72. A spring 73 tends to draw the 65 latch element 71 towards latching position. The lever 64 is provided with a nose 74 which is adapted to engage an extension 75 on the latching element 71. When the lever 64 is in retracted position, which condition is shown in Fig. 2, the 70 nose 74 is in engagement with the extension 75 and the latch element is held in non-latching position. When, however, the bar 46 moves to the left, as viewed in this figure, the latching element is free to move under the action of the 75

spring 73 towards latching engagement with the down-turned ends of the three levers 76, 77, 78. These levers are pivotally supported on a post 79 carried by the plate 25. The levers 76, 77, 78 5 are biased by springs 80 so that their operative ends 81, 82 and 83 are biased towards the ratchet wheels 34 and 33. The operative end 81 of the lever 76 is provided with a roller which is adapted to move into the path of the teeth of the 10 ratchet wheel 34 when the latch element 71 moves to unlatched position. The lever 77, at its operative end 82, carries a similar roller which is adapted when it is unlatched to move into the path of the teeth of ratchet wheel 33. 15 In the event that the last mentioned roller becomes arrested at the top of a tooth, the down-turned operative end of the lever 78 strikes the ratchet wheel 33 and causes it to rotate slightly so that the roller at the operative end 82 of the 20 lever 77 may move into the recess between two teeth of the ratchet wheel 33. The down-turned ends of the levers 76, 77, 78 are arranged so that the latching element 71 first releases the lever 76 so as to arrest the horses, then the lever 77 25 is released to arrest the plate 28, and then the lever 78 is released so as to align the cylinder 30 accurately.

The latch member 71 is provided with a slot 84. It is also provided with a projecting lip 85 30 which is adapted to engage and latch the extremity 86 of a lever 87 pivotally mounted on the plate 25. At the opposite end of the lever 87 is an upstanding tooth 88 which tends to move into the path of the ratchet wheel 34. The lever 87 35 is released after the lever 76 and in the event that the roller at the operative end 81 of the lever 76 should become arrested at the peak of a tooth on the ratchet wheel 34, then the lever 87 will strike against one of the teeth of the ratchet 40 wheel 34 so that the roller at the operative end 81 of the lever 76 may drop into a recess between adjacent teeth of the ratchet wheel 34. The lever 76 has rigidly secured thereto a forwardly extending arm 89 which lies in the path of a pin 45 90 which projects upwardly from the bar 46. The arm 89 carries an upstanding member 91 which is adapted to engage the two levers 77 and 78. When the bar 46 is moved to the left, as viewed in Fig. 2, the pin 90 engages the arm 89 50 and swings the three levers 76, 77, 78 into line with the slot 84 on the latch element 71. The lever 87 carries an upstanding projection 92 which is also engaged by the arm 89 so as to swing its projection 86 into position so that it 55 may be engaged by the lip 85 of the latch member 71. The latch member 71 is moved by the spring 73 into latching engagement with the levers 76, 77, 78 and 87, the nose 74 being moved away from the extension 75 of the latching element 71 as the lever 64 moves to the left with the bar 46. The lever 87 is biased away from latched position by means of a spring 93.

The cylinder 30 is provided with openings 94 arranged in series around its circumference. The 65 number of series of openings corresponds to the number of horses, there being six series of openings in the embodiment shown, as will best be seen in Fig. 4. The openings 94 are displaced vertically around the periphery of the cylinder, as will 70 best be seen in Fig. 3. This spacing of the openings is correlated with the indicia on the margin of the plate 28. The relation of these openings may best be explained with reference to Fig. 4. The horse on the left-hand side of this figure is 75 the selected horse and has won, being stopped at

the winning post by the mechanism previously described. As a result of this selection by the operator before the play, the finger 95 finds itself in alignment with the opening 27 corresponding to that horse. There is always one opening 94 5 in alignment with the finger 95, this being insured by the accurate stopping of the cylinder 30 which has previously been described. Consequently, the finger 95, when projected to the right as viewed in Fig. 4, will extend through that particular 10 opening 94 and through the particular opening 27. The extent of its projection depends upon the vertical placement of the particular opening 94 since the operative end of the finger 95 is stepped. If the selected horse does not win, there 15 is no opening 27 in alignment with the finger 95 and this finger is arrested, as will be understood more clearly from the subsequent description, by contact with the exterior of the cylinder 26. If the horse wins with the lowest odds, the finger 95 20 may proceed to the right until the first step engages the exterior of the cylinder 30. If the horse wins with the next highest odds, the finger may proceed to the second step and so forth, with results hereinafter to be described. The finger 95 25 has a number of vertical positions corresponding to the number of horses and the number of series of openings 94.

The finger 95 is provided with two slots 96 through which extend two flatheaded pins 97. 30 The slots 96 are horizontal so that the finger moves in the horizontal direction. The pins 97 are carried by a plate 98 which extends vertically through a slot 99 in the plate 25. At its top and bottom the plate 98 has laterally extended flanges 100 which are provided with openings. Through these openings 100 passes a vertical bar 101 which is supported by a casting 102 rigidly mounted on the plate 25. This casting provides upper and lower bearings for a shaft 103 which passes 40 through an opening in the top flange 100 of the plate 98 and serves to preserve this plate in vertical condition.

Along its forward edge the plate 98 is provided with semi-circular notches 104, which are six in 45 number corresponding to the number of horses. These notches are equally spaced, the distance between them being equal to that between adjacent series of openings 94 on the cylinder 30. These notches are adapted to receive a roller 105 50 mounted on a lever 106 which is pivotally mounted on an angle iron 107 carried by the plate 25. The lever 106 is normally held by a spring 108 so as to force the roller 105 into one of the notches 104. The notches 104 are so positioned that the 55 roller 105 holds the finger 95 in operative relation with one of the series of openings 94 on the cylinder 30. The vertical movement of the plate 98 is limited by the engagement of its bottom flange 100 with the underside of the plate 25 and by the 60 engagement of its upper flange 100 with a collar 109 carried by the rod 101 so that the roller 105 can always enter one of the notches 104.

The selector handle 14 is rigidly mounted on a pin 110 which is mounted on a lever 111, which lever is pivotally mounted on an angle iron 112 which is mounted on the plate 25. The lever 111 extends through an inverted U-shaped guide 113 and terminates adjacent the face of the plate 98. It is maintained in a mid position by means of 70 oppositely directed springs 114, so that it is free to swing up or down when actuated by the selector handle 14, as may be desired. This swinging movement in either direction is limited by set screws 115 mounted on the guide member 113 and 75

on the plate 25. Adjacent its free end, the lever 111 has pivotally mounted upon it two diverging fingers 116 which have pointed ends adapted to enter openings 117 formed in the plate 98. These 5 openings have the same spacing as the notches 104 and are eight in number. The curved points of the fingers 116 are separated by a bar 118 supported from the plate 25, as shown in Fig. 4. They are connected together by means of a spring 119 and are adapted to engage a pin 120 mounted 10 between them, as best seen in Fig. 3. Referring to Figs. 3 and 4 it will be noted that the ends of the fingers 116 normally project towards two openings 117. When the lever 111 is swung upwardly 15 the lower finger 116 is detained by the bar 118 and is swung away from the plate 98. The spring 119 and the upward movement of the pivot of the upper finger 116 causes this finger to project into the opening towards which it was directed. The swinging of the upper finger 116 brings it into contact with a pin 120 and thereafter the upward movement of the lever 111 forces the plate 98 upwardly. This movement is limited by the pin 115 so that the plate 98 moves upwardly by a 20 distance equal to the spacing of the notches 104. If the selector handle 14 is pressed downwardly, the reverse operation occurs, the upper finger 116 being withdrawn from the plate 98 and the lower finger 116 becoming effective to thrust the plate 25 downwardly by a distance equal to the spacing of the notches 104.

The plate 98 is provided with an opening 121 which receives the reduced end of a lever 122. This lever is pivotally mounted on the angle iron 35 112. The lever 122 is connected by a link 123 to a short arm 124 of a lever 125. The lever 125 carries a sector 126 which bears indicia, such as numbers and colors corresponding to the numbers and colors of the horses 13. It will be readily understood that six parts of the sector 126 40 may be observed through the opening 15 and these portions correspond with six positions of the finger 95, which in turn corresponds to the six series of openings 94 in the cylinder 30 and 45 to the six openings 27 in the cylinder 26, each of the openings 27 corresponding to one of the horses and to the similarly marked portion of the sector 126. It will readily be understood that when a certain horse wins, that is, when the disc 20 becomes arrested with one of the openings 27 in alignment with the finger 95, then the 50 visible portion of the sector 126 shows the same number and color as the horse at the winning post. The weight of the plate 98 and associated parts is counterpoised to some extent by a spring 55 127 connected to the angle iron 112 and to the end of the lever 122 remote from the plate 98.

The plate 98 is provided along its rear edge, that is the edge opposite the notches 104, with a series of slots 128 spaced vertically at distances equal to the distance between the centers of adjacent notches 104. The slots 128 are so located that one of them is located immediately above the plate 25 when the roller 105 is located in one of the notches 104.

A bar 129 is slidably mounted on the plate 28 in alignment with the slot in this position. The bar 129 is slidably mounted on the plate 25 by means of pins 130 which extend through slots in the bar. At its end remote from the plate 98, the bar 129 is provided with an upturned end 131 which is adapted to be engaged by the bar 64. In the initial position of the bar 64, the bar 129 is held out of the slot 128. When, however, the bar 64 is moved from its initial position and while

it is returning slowly thereto, the bar 129 is held by a spring 132 within the slot 128. A stop 133 prevents excessive movement of the bar 129. The bar 129 serves to lock the selector during the play and the selector becomes unlocked again only after the spinning mechanism has become arrested and the finger 95 has performed its function, which function will now be described.

The finger 95 comprises an integral horizontal flange 134. This flange is provided with a slot 10 135 through which extends freely a screw 136 rigidly mounted in an arm 137. The arm 137 is integral with a collar 138 which is slidably mounted upon the shaft 103. The shaft 103 is provided with a longitudinal keyway 139 into which extends a projection 140 carried by the collar 138. Consequently, whenever the shaft 103 is rotated in counter-clockwise direction, as viewed in Fig. 2, the finger 95 is caused to slide towards the cylinders 26 and 30. The collar 138 is provided with a circumferential groove 141 which receives a horizontal fork-shaped member 142 which is integral with the plate 98. This engagement causes the collar and plate to slide together vertically when the selector is actuated.

On the underside of the plate 25, the shaft 103 has rigidly mounted thereon an arm 143. This arm has pivotally secured thereto a link 144. The link 144 is pivotally connected to a lever 145 pivotally mounted at one end on the underside of the plate 25. At its opposite end the lever 145 carries a roller 146. The link 144 is provided at one end with a slot 147 through which passes a screw 148 rigidly mounted in an arm 149. The arm 149 is rigidly mounted on the lower end of a shaft 150 which projects upwardly through the plate 25. A spring 151 secured to the lever 145 and to the plate 25 tends to move the connected system so as to move the finger 95 towards the cylinders 26 and 30. The finger 95 40 is normally held away from the cylinders 26 and 30 by means of a more powerful spring 152 which is secured to the underside of the plate 25 and to a lever 153.

The lever 153 is provided at one end with an elongated slot 154 whereby the lever is pivotally mounted on the underside of the plate 25 by means of a screw 155 extending through said slot. The lever 153 is connected to a link 156 which is provided with an elongated slot 157 through which passes a pin 158 carried by the arm 143.

The normal or initial position of the mechanism is shown in Fig. 5, that is, the spring 152 is contracted and the arm 143 is held against movement by the spring 151 owing to the presence of the pin 158 at the end of the slot 157. The shaft 65 on which the arm 64 is rigidly mounted extends through the plate 25 and through the timing mechanism previously referred to, and carries rigidly at its lower end a lever 159. This lever is pivotally connected to a link 160 which, in turn, is pivotally connected to a lever 161 pivotally mounted on the underside of the plate 25 by means of a screw 162.

One end of the lever 161 is adapted to engage a pin 163. When the handle 16 is actuated, the lever 161 engages the pin 163 and moves the link 166 to the left, as viewed in Fig. 5. The link 166 is provided with an elongated slot 164 which is provided at one end with an extension 165. A latch element 166 projects downwardly from the plate 25 into the slot 164. When the link 166 is moved the full distance by the lever 161, the spring 152 pulls the links 153 and 156 upwardly.

as viewed in Fig. 5, with the result that the latch member 166 enters the extension 165 and the link 156 is thus maintained latched until after the timing mechanism is operated for a predetermined period of time. The unlatching is effected by an arm 167 of the lever 161 engaging the downturned end 168 of a bar 169 slidably mounted on the underside of the plate 25. The bar 169 has at its other extremity a downturned end 170 which is adapted to engage the link 156. The bar 169 is biased by the spring 171 so that its extremity 170 is out of contact with the link 156. When, however, near the end of the operation of the timing mechanism the arm 167 engages projection 168, the link 156 is moved slightly so as to locate the latch 166 in the main length of the slot 164. When this occurs the strong spring 152 moves the links 153 and 156 into the position shown in Fig. 5.

20 When the handle 16 is first actuated a cam 172, which may suitably be integral with the arm 159, is moved into cooperation with the roller 146 so as to prevent movement of the lever 145 under the action of the spring 151 which would result 25 in the projection of the finger 95 towards the cylinders 26 and 30 while they are spinning. The cam 172 is relatively broad so as to prevent this movement of the lever 145 until near the end of the operation of the timing mechanism. The sequence of the operation of the elements just described is as follows: First the hand operation of the machine causes the cam 172 to move into a position opposite the roller 146. Second, the same movement causes the link 161 to move the 30 link 156 to latched position. This latched position affords a degree of freedom for the arm 143, but movement of this arm is prevented by the engagement of the roller 146 with the cam 172. Third, the automatic operation of the timing mechanism locks the disc 20 and the plate 28 in 35 the manner previously described and then moves the cam 172 away from the roller 146, whereupon the spring 151 rotates the arm 143 in the clockwise direction, as viewed in Fig. 5. This movement of the arm 143 causes the finger 95 to project towards the cylinders 26 and 30. Consequently, the movement of the arm 143 and link 144 is dependent upon the openings 94 and 27 which may find themselves in alignment with the 40 finger 95, and fourth, the continued movement of the arm 159 under the action of the timing mechanism effects the unlatching of the link 156 so that the strong spring 152 moves it into the position shown in Fig. 5. This movement of the link 45 156 effects the withdrawal of the finger 95 from the cylinders 26 and 30. Thus it will be seen that the shaft 150 receives an oscillation in the clockwise direction, as viewed in Fig. 5, which is dependent upon the openings 94 and 27 which may 50 be left in front of the finger 95 at the end of the spinning of the discs 20 and 28, and then an oscillation in the opposite direction to its initial position.

The shaft 150 extends upwardly through the 55 plate 25 and is supported on a bearing 173 mounted on the plate 25. At its upper end the shaft 150 has rigidly mounted thereon a yoke element 174 having two horizontal arms 175. These arms are provided with oppositely directed pins 176 which extend into the annular space 177 between two collars 178 rigidly mounted on a rod 179. The rod 179 is mounted for sliding movement in the longitudinal direction so that it moves a distance corresponding to the movement 60 of the finger 95 whenever that finger is actuated.

The rod 179 is supported at one end by the reduced portion 180 of a shaft 181, which reduced portion extends into a bore at said end of the rod 179. At its forward end the rod 179 is supported by passing through an opening 182 in a supporting member 183 which is mounted on the plate 25. The supporting member 183 carries a key 184 which extends into a keyway 185 in the rod 179 and prevents this rod from turning.

The rod 179 also passes through a supporting member 186 also mounted on the plate 25. The rear end of the rod 179 is provided with a flange 187 and a star wheel 188 is mounted on the rod 179 adjacent the flange. The star wheel 188 is held in position by means of a collar 189 rigidly 10 mounted on the rod. The collar 189 is provided with a spring-pressed ball 190 which is adapted to enter into openings 191 on the adjacent face of the star wheel 188 so as to hold the star wheel 15 in set position for a purpose which will herein- 20 after be apparent.

The star wheel 188 is provided with a rearwardly extending post 192 which carries a spring-pressed pawl 193 which is adapted to cooperate with ratchet teeth 194 formed on the shaft 181. 25 The ratchet teeth 194 are relatively long so that the pawl 193 may remain in contact therewith, notwithstanding a considerable sliding movement of the rod 179 relative to the shaft 181. The shaft 181 is rotatably mounted in a bearing 195 and is 30 held against longitudinal movement by means of a pin 196 which extends into an annular groove in the shaft. Adjacent its rear end the shaft 181 carries a radially projecting pin 196 which extends freely through an elongated slot 197 in a 35 short arm 198 which is rigidly mounted on the shaft 51. Every time the handle 16 is actuated, the shaft 181 is oscillated in one direction and then oscillated in the opposite direction back to its initial position. The effect of these oscillations is to rotate the star wheel 188 through a predetermined angle in one direction. The angle through which the star wheel 188 is turned is correlated with the number of teeth 199 on the star wheel 188. With five teeth, a rotation of 36 45 degrees is suitable, this being the angle through which the star wheel 188 turns in order to bring a gap 200 into the position occupied by one of the next adjacent teeth 199. The teeth of the star wheel 188 rotate through slots 201 formed in rack 50 bars 202. These rack bars are guided in suitable openings in the supports 183 and 186. They are drawn rearwardly by springs 203, the rearward movement being limited by stops 204, which engage the support 186. These rack bars 202 are 55 located in diametric opposition relative to the star wheel 188.

As readily seen in Fig. 7, owing to the odd number of teeth 199, one of these teeth is located within the slot 201 of one of the bars 202 so that when 60 the star wheel 188 is moved in an axial direction that tooth will engage that bar and actuate it, whereas the other bar 202 will remain unaffected. In Fig. 7 the bar 202 on the left-hand side is the one which can be actuated by the star wheel 188. 65 After the handle 16 has been actuated the condition will be reversed and the star wheel 188 will be brought into position for operation of the right-hand bar 202. Thus it will readily be understood that as the device is operated a successive number of times, the bars 202 are operated alternately and the degree of movement imparted to them depends upon the movement of the finger 95 which causes their operation. The slots 201 are somewhat larger than the thickness of the 70 75

teeth of the star wheel 188 so that a degree of free motion of the star wheel, corresponding to the movement of the finger 95 through one of the openings 94 into contact with the cylinder 26, is permitted without any corresponding actuation of the bar 202. If, however, the finger 95 moves to a greater extent owing to the presence of the appropriate opening 27 in alignment with the finger, then the appropriate bar 202 is moved longitudinally. The degree of this movement depends upon the particular opening 49 through which the finger 95 passes. From the previous description it will readily be understood that this degree of movement may correspond to odds of 1, 2, 3, 4 or 5.

The bars 202 are adapted to cooperate with pinions 205 of the counters 18 so that the odds acquired by each player or each team is added up separately and alternately on the two counters 18. The readings of these counters are visible through windows 207 in the wall of the cabinet, and the readings of the counters can be returned to zero by actuating the button 17 located on the exterior of the cabinet.

It is believed that the operation of the device will readily be understood from the foregoing description. For the sake of completeness a short description of the operation is now given.

The button 17 is first actuated to bring the readings of the counters 18 to zero. Then the first player actuates the selector handle 16 so as to bring the number and color of the horse he selects to win into register with the window 15. Then he actuates the handle 16, spinning the disc 20 and plate 28, latching the link 156 in an operative position and moving the cam 172 so as to prevent movement of the finger 95. The selector becomes locked owing to the movement of the lever 64 from normal position. The gradual return of this lever against the opposition of the timing mechanism arrests the disc 20 and then the plate 28. Then the cam 172 clears the roller 146 and allows the spring 151 to move the finger 95 towards the cylinders 26 and 30 to an amount depending upon the openings which may be in alignment with the finger. This movement is communicated to the particular counter indicating the results of that player. If the selected horse does not win, the reading of that counter 50 remains at zero. If the horse wins, the appropriate opening 27 is left in alignment with the finger 95 and the extent of the movement of the finger depends upon the location of the opening 49 which is left in alignment with the finger. Consequently, the appropriate odds are added to the reading of the counter. The machine is next operated by the opposing player in the same manner, except that owing to the alternation provided by the star wheel 188, the winning score, if any, is recorded in the other counter.

Although the invention has been disclosed in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. A game apparatus comprising two separate rotatable members, concentric cylinders on said members located one within the other, said cylinders being provided with openings, a generally tapering finger adapted to enter an opening in the outer cylinder and into any opening in the

inner cylinder in alignment therewith, means forcing said finger into said openings, and means for withdrawing it therefrom, the openings in the inner cylinders being at various heights to vary the degree of entry of said pin.

2. A game apparatus comprising two separate rotatable members, two cylinders on said members, one within the other provided with openings, a finger adapted to enter aligned openings in said cylinders, means for spinning said members, means for arresting said members, means for forcing said finger into said openings, means on said finger for engaging one of said cylinders to limit the entry of said finger, and means actuated by said finger in accordance with the degree of entry of said finger.

3. A game apparatus comprising two separate rotatable concentric members provided with openings, means for arresting said members, a stepped finger adapted to enter openings in alignment therewith and engage one of said concentric members to limit said entry, resilient means forcing said finger into said openings, and means for withdrawing it therefrom.

4. A game apparatus comprising two separate rotatable concentric members provided with openings, means for arresting said members, a generally tapered finger adapted to enter openings in alignment therewith and engage one of said concentric members, resilient means forcing said finger into said openings, means for withdrawing it therefrom, and means actuated by said finger corresponding to the degree of the entry of the finger into the openings.

5. A game apparatus comprising two separate rotatable concentric members provided with openings, means for arresting said members, a generally tapered finger adapted to enter openings in alignment therewith to the degree permitted by the location of the openings, the finger being adapted to be arrested by engagement with one of said concentric members, resilient means forcing said finger into said openings, means for withdrawing it therefrom, and a counter actuated by said finger to a degree corresponding to the degree of entry of the finger into the openings.

6. A game apparatus comprising two separate rotatable concentric members provided with openings, means for arresting said members, a generally tapered finger adapted to enter openings in alignment therewith to the degree permitted by the location of the openings, the finger being adapted to be arrested by engagement with one of said concentric members, resilient means forcing said finger into said openings, means for withdrawing it therefrom, a pair of counters adapted to be actuated by said finger to a degree corresponding to the degree of entry of the finger into the openings, and means for alternately connecting said finger to said counters.

7. A game apparatus comprising two separate rotatable concentric members provided with openings, means for arresting said members, a generally tapered finger adapted to enter openings in alignment therewith to the degree permitted by the location of the openings, the finger being adapted to be arrested by engagement with one of said concentric members, resilient means forcing said finger into said openings, means for withdrawing it therefrom, means for spinning the rotatable members, and delayed means for arresting said members with openings therein in alignment, for forcing the finger into said open- 75

ings, and for withdrawing said finger in the order stated.

8. A game apparatus comprising two separate rotatable concentric members provided with 5 openings, means for arresting said members, a stepped finger adapted to enter openings in alignment therewith, resilient means tending to force said finger into said openings, stronger resilient means tending to hold said finger out of said 10 openings, a timing mechanism, a cam adapted to hold said finger against actuation by the first said resilient means, means for spinning the rotatable members, rendering said stronger resilient means inoperative and energizing said timing mechanism, and bringing the cam into operative 15 position, and means for arresting said members with openings therein in alignment controlled by said timing mechanism, said timing mechanism being adapted to move said cam to 20 an inoperative position, thereby permitting the first said resilient means to project the finger into said openings, and to release the stronger resilient means to effect the withdrawal of said finger.

25 9. In a game apparatus, in combination, a pair of concentric cylinders, one of said cylinders having a plurality of large openings in one cylinder arranged at different heights, the other cylinder having a corresponding number of circumferential 30 series of openings, each series being adapted to cooperate with one of the first said openings, each series having its openings staggered in the vertical direction, and a finger having a series of cylinder-engaging surfaces located at various 35 heights distributed in the longitudinal direction of the finger, said finger being adapted to enter into aligned openings to a varying degree depending upon the location of the particular openings.

10. In a game apparatus, in combination, a 40 pair of concentric cylinders, one of said cylinders having a plurality of large openings in one cylinder arranged at different heights, the other cylinder having a corresponding number of circumferential series of openings, each series being 45 adapted to cooperate with one of the first said openings, each series having its openings staggered in the vertical direction, a finger having a series of cylinder-engaging surfaces located at various heights distributed in the longitudinal 50 direction of the finger, said finger being adapted to enter into aligned openings to a varying degree depending upon the location of the particular openings, and means for moving said finger to various heights to cooperate with a desired one of said series.

55 11. In a game apparatus, in combination, a pair of concentric cylinders, one of said cylinders having a plurality of large openings in one

cylinder arranged at different heights, the other cylinder having a corresponding number of circumferential series of openings, each series being adapted to cooperate with one of the first said openings, each series having its openings 5 staggered in the vertical direction, a finger having a series of cylinder-engaging surfaces located at various heights distributed in the longitudinal direction of the finger, said finger being adapted to enter into aligned openings to a varying degree depending upon the location of the particular openings, means for moving said finger to various heights to cooperate with a desired one of said series, and means actuated by said finger to a degree depending upon the degree of entry of the finger into said openings.

12. In a game apparatus, in combination, a pair of concentric cylinders, one of said cylinders having a plurality of large openings in one cylinder arranged at different heights, the other 20 cylinder having a corresponding number of circumferential series of openings, each series being adapted to cooperate with one of the first said openings, each series having its openings 25 staggered in the vertical direction, a finger having a series of cylinder-engaging surfaces located at various heights distributed in the longitudinal direction of the finger, said finger being adapted to enter into aligned openings to a varying degree depending upon the location of the 30 particular fingers, means for moving said finger to various heights to cooperate with a desired one of said series, and a counter actuated by said finger to a degree depending upon the degree of entry of the finger into said openings.

13. In a game apparatus, in combination, a pair of concentric cylinders, one of said cylinders having a plurality of large openings in one cylinder arranged at different heights, the other cylinder having a corresponding number of circumferential series of openings, each series being 40 adapted to cooperate with one of the first said openings, each series having its openings staggered in the vertical direction, a finger having a series of cylinder-engaging surfaces located at various heights distributed in the longitudinal direction of the finger, said finger being 45 adapted to enter into aligned openings to a varying degree depending upon the location of the particular fingers, means for moving said finger to various heights to cooperate with a desired one of said series, a pair of counters actuated alternately by said finger to a degree depending upon the degree of entry of the finger into said openings, and means for connecting each counter 50 to the finger.

GUSTAVE ERICKSON.
